UNITED STATES PATENT OFFICE.

CHARLES H. HOWARD, OF SAUGUS, MASSACHUSETTS, ASSIGNOR TO PAPER PRODUCTS MACHINE COMPANY, OF BOSTON, MASSACHUSETTS, A CORPORATION OF MASSACHUSETTS.

PAPER-REINFORCING MACHINE.

1,278,471.

Specification of Letters Patent. Patented Sept. 10, 1918.

Application filed December 29, 1916. Serial No. 139,475.

To all whom it may concern:

Be it known that I, CHARLES H. HOWARD, a citizen of the United States, residing at Saugus, in the county of Essex and State of Massachusetts, have invented an Improvement in Paper-Reinforcing Machines, of which the following description, in connection with the accompanying drawings, is a specification, like characters on the drawings representing like parts.

The invention to be hereinafter described relates to machines for reinforcing fabrics, and more particularly to such machines for reinforcing paper fabrics by the application 15 of transverse threads thereto. The invention is an improvement upon the machine disclosed in my co-pending application, Serial Number 134,259, filed December 1, 1916.

In accordance with the machine shown in 20 the said application, the reinforcing elements, which may be threads, cords, wires, or similar filaments, are carried transversely of the machine or placed in transverse relation to the fabric to be reinforced. The 25 means for carrying the filaments transversely may be in the form of a series of grippers which move transversely of the machine and then the filaments are freed from the grippers and applied to a receiver. 30 This receiver may be in the form of a carrier, preferably one at each side of the machine, which takes the transverse filaments from the grippers and carries them in a direction longitudinally of the machine for 35 delivery upon the fabric to be reinforced.

It is desirable that the carriers should be provided with means for effectively holding the transverse filaments as they are thus conducted longitudinally of the machine, 40 and an important feature of the invention relates to electric means for holding the filaments as they are conducted in this manner by the carriers.

In accordance with the machine shown in 45 said prior application, the filaments are conducted from a source of supply at one side of the machine to the grippers and are then distended by the latter transversely of the machine. It is therefore desirable to sever the transverse threads from their supply

after they have been conducted as described, transversely of the machine. An important feature of the invention relates to simple and effective means for severing the filaments from their source of supply.

The broad features of the invention referred to may be carried into effect by various detailed forms of mechanisms, one good embodiment of which is illustrated in the accompanying drawings. The character 55 of the invention will be best understood from the following description of this embodiment of the invention shown in the accompanying drawings, wherein:

Fig. 1 is a vertical transverse section 65 through one of the grippers at the supply side of the machine, the truck supporting the same, the track upon which the truck travels, a cutter carried by the truck; the carrier for holding the threads as they are 70 conducted longitudinally of the machine, and a portion of the frame for guiding the carrier;

Fig. 2 is a vertical transverse section 75 through the gripper truck, the track and cutter shown in Fig. 1, but with the cutter in different position, and the filament-taking gripper truck and track coöperating therewith;

Fig. 3 is a side elevation of a portion of 80 the carrier and filament-holding devices for conducting the filaments longitudinally of the machine and an electrical device for controlling the operation of said devices;

Fig. 4 on an enlarged scale, is a detail side 85 elevation of one of the holding devices mounted on the carrier, certain parts being broken away more clearly to disclose the detail of the device.

Fig. 5 is a vertical section taken on the 90 line 5—5 of Fig. 4;

Fig. 6 is a view similar to Fig. 4, showing certain elements thereof in different position;

Fig. 7 is a plan of the holding device 95 shown in Fig. 6;

Fig. 8 is a perspective view of the clamping fingers forming a part of the holding device;

Fig. 9 is a longitudinal elevation showing 100

a portion of one of the carriers, the holding devices on the carrier, and the cutting mechanism coöperating with said holding devices; and

6 Fig. 10 is a plan of a mechanism for locking and releasing the cutter-actuating hammers.

10 Referring to the drawings:—The main frame of the machine may be of any desired character suitable for sustaining the operating parts, and may conveniently be of the form shown in said prior application.

15 The grippers for distending the filaments transversely of the machine may be constructed the same as the grippers shown in said prior application, and therefore need not be described in detail herein; but it will suffice to say that the grippers on the gripper carrier at the supply side of the machine each 20 comprises a fixed lower jaw member 1 which coöperates with an upper jaw member 3 normally under the influence of a spring tending to open the jaw members. A cam or projection 5 is mounted on a shaft 7 and is 25 adapted to close said jaw members on rotation of said shaft; as will be evident from Fig. 1.

30 The grippers at the opposite or filament-taking side of the machine also may be similar to the taking grippers shown in the said prior application and comprise upper and lower jaw members 9 and 11 adapted to be opened by a spring 13 and closed by a rotatable cam 15.

35 The grippers at the supply side of the machine are carried by brackets 17 depending from a truck 19 having rollers 21 adapted to travel longitudinally on a track 23 carried by an I-beam 25.

40 The grippers at the opposite side of the machine are similarly carried by a bracket 27 depending from a truck 29 having rollers 31 adapted to travel along a track 33 carried by an I-beam 35.

45 These I-beams may be moved toward and from one another transversely of the machine to cause the supply and taking grippers to approach and recede from one another to distend the filaments transversely of the machine by a mechanism similar to that disclosed in said prior application, and therefore unnecessary to show and describe herein.

50 Next will be described the receiver for the filaments conducted transversely of the machine. As stated, this receiver may be in the form of a carrier at each side of the machine, and since these carriers are similar, a description of one will suffice for both. The 55 carrier comprises a sprocket chain 37, Fig. 3, supported by sprocket wheels such as 39 mounted on the shafts such as 41 journaled in bearings in a side frame 43 having a hori-

zontal top flange 45 for supporting the upper run of the sprocket chain and causing 65 the same to travel in a rectilinear path.

The sprocket chain comprises a series of links, each of which may be provided with devices for receiving and holding the filaments delivered thereto from the grippers, 70 and since these devices are similar, a description of one will suffice for all. Each of these devices comprises an upward extension 47 (Figs. 4, 5 and 6) having a V-shaped groove 49 which engages and travels along 75 a guide 51, Fig. 1, to further contribute to the positive guidance of the upper run of the chain in a rectilinear path.

Extending upwardly from this extension 80 is a plate 53 having a series of teeth 55 projecting upward and offset laterally from the top edge thereof. Coöperating with these teeth are a series of fingers 57 preferably of resilient material and secured to a back bar 59 adapted to reciprocate in a recess in a block 61 mounted on the extension 47 and projecting upwardly opposite the toothed plate 53. The spring fingers are adapted to reciprocate in this space toward and from the teeth 55 and said fingers and teeth 90 co-operate as jaws to clamp the filaments between them. To facilitate the entrance of the filaments between them, said teeth may have pointed heads 63 and shoulders 65 adapted to overlie the upper ends 95 of said fingers when the latter are in open position to insure guidance of the filaments properly between the teeth and fingers. Preferably, the fingers are inclined somewhat from the vertical to the right, 100 Fig. 5, so that on movement toward the teeth to grasp the filaments between them, the fingers will flex to a vertical position and thus be tensioned and provide a desirable pressure which will insure secure retention 105 of the filaments.

To shift said spring fingers to the left of Fig. 5, in readiness to receive the filaments, the bar 59 may be provided with an L-shaped arm 67, Fig. 7, connected by a helical spring 110 69 with a pin 71 fixed on the block 61 referred-to. To shift said fingers to the right to grasp the filaments between said teeth and fingers, suitable electrical means may be provided typified herein in the form of a solenoid 73 mounted on the block 61 and having a core 75 connected to the bar actuating arm 67. When the solenoid is energized, it will draw its core to the right; Figs. 4 and 7, and thereby shift the finger bar 59 toward the right and cause the fingers to press the filaments against the teeth 55. When the core is deenergized, the spring 69 will be effective to shift said bar in the opposite direction and move the fingers to their position shown in Fig. 4, where they are in

readiness to permit the introduction of the transverse filaments between said fingers and teeth.

Next will be described means for automatically energizing the solenoids at the proper times in the cycle of operations of the machine to grasp the filaments on the carrier as they are presented thereto by the grippers.

10 It will be understood that in the operation of machines of this class, the filaments are first distended transversely of the machine; then lowered toward the carrier; then moved longitudinally of the machine a certain distance with the carrier; then the filaments are grasped by the carrier; then they are released from said grippers and conducted longitudinally of the machine to the fabric to be reinforced.

20 After the grippers have delivered the filaments to the carrier, they are retracted longitudinally of the machine and in the course of this movement they may be moved toward one another transversely of the machine to bring the taking grippers into the positions where they will be in readiness again to receive the filaments from the grippers at the supply side of the machine. While the grippers are retreating, the carrier is advanced longitudinally of the machine so that the holding devices on the carrier supplied with the transverse threads are conducted forward and a set of empty holding devices on the carrier are brought 35 within range of the grippers in readiness to receive the transverse filaments therefrom.

Therefore, the holding devices approaching the range of the grippers should be de-energized and open in readiness to receive 40 the filaments, whereas the set of holding devices which have just passed within the range of the grippers and have received the filaments therefrom, should be energized to hold said filaments.

45 To accomplish this, a contact rail 77, Fig. 3, may be mounted on the sprocket chain guiding frame 45 and be separated therefrom by insulation pieces 79. A battery 81 or other suitable source of electricity may 50 be connected to a conductor 83 which may be grounded at the point 85 on the frame 45. The other side of the battery may be connected by a conductor 87 with a branch conductor 89 connected in turn to a brush 55 91 coöperating with a conducting hub 93 of a commutator 95. The hub 93 may be connected by a conductor 97 with a segment 99 of said commutator having ends terminating with a substantial space of interruption 60 101 between them. A contact or brush 103 is adapted to engage with said contact segment on rotation of the commutator and make or break the circuit according to

whether or not said brush is in engagement with said contact segment or is opposite the interruption between the ends of said segment. The contact 103 may be connected by a conductor 105 with the contact rail 77 referred-to.

The commutator may be connected with 70 any convenient rotating element of the machine, but should be caused to turn one complete rotation for each complete cycle of movement of the grippers, that is, the commutator should make one complete rotation 75 each time the grippers are separated transversely of the machine, lowered, moved longitudinally of the machine, retreated and caused to approach. The rotation of the commutator also should be so timed that the 80 circuit to the contact rail will be completed while a holding device is traveling the length of said rail.

To conduct the current to the coil of the solenoid one of said coils may be connected 85 to a contact shoe 107, Fig. 3, adapted to slide along the contact rail 77 and the other end of said coil may be connected to a contact shoe 81 adapted to slide along the top of the frame 45. Thus, when a holding device in the course of its orbit on the carrier reaches the contact rail, its contact shoe 107 will contact therewith and the circuit will be completed to the coil, thereby energizing the solenoid and shifting the bar 59 and fingers 90 57 to the right of Figs. 5 and 6, and causing the fingers to press the filaments against the teeth 55 and securely hold the same.

In the present embodiment of the invention, the contact rail 77 has been shown of 100 a length sufficient to energize simultaneously six holding devices, but obviously the length of this rail may be varied to energize any number of holding devices desirable.

The energization of these devices should 105 continue until they have had an opportunity to conduct the filaments to the fabric to be reinforced. Accordingly, it is found convenient to provide a second contact rail 109, Fig. 3, which will continue the energization 110 of the holding devices for a period after they have left the first rail referred-to. The rail 109 may be also mounted upon the frame 45 and be supported therefrom by insulation pieces 111. This rail may be connected 115 to the conductor 87 leading from the battery by a conductor 113. The conductor 113 will not be affected by the rotation of the commutator, and consequently, current from the battery will continuously stand on the frame 120 45 and rail 109, and thus, when the holding devices come into contact with said rail and frame, their solenoids will be energized.

The rails 77 and 109 do not meet, but have a space between them to permit the 125 independent electrical control of said rails.

4
Current is supplied to the rail 77 intermittently, whereas current is supplied to the rail 109 continuously. However, the contact shoes 107 are made of sufficient length so that they will bridge the space between the contact rails and engage the rail 109 before leaving the rail 77. Thus, the devices after being energized in their transit over the rail 77, continue to be energized 10 for a period after leaving said rail determined by the length of the rail 109.

It will be understood that a series of filaments are lowered simultaneously by the grippers to a set of the holding devices and consequently, it is desirable that these holding device should be simultaneously energized in order to cause the grippers simultaneously to grip the series of filaments. The rotation of the commutator is so timed 20 that all of these holding devices 57 will be simultaneously energized. The current will be maintained on said rail until the last of the devices thus energized will have an opportunity to leave said rail. As the leading holding device is passing from the rail 77, another holding device will pass onto said rail and of course immediately on its arrival, will be energized, but it will be ineffective 25 to hold any filament. All of the holding devices on the rail thus follow along on the rail, and after being energized thereby, will be deenergized by the interruption in the commutator so that the holding devices will be open a sufficient interval to allow a following set of filaments to be lowered between their clamping jaws.

Thus, the holding devices as they progress in their order, will successively become effective to receive, hold, and conduct the transverse filaments to the fabric to be reinforced.

As stated, the filaments should be severed from their source of supply after being conducted transversely of the machine in order that the grippers may be effective to distend 45 a following set of filaments transversely of the machine. Next will be described a simple and effective cutting mechanism for severing the filaments from their supply after they have been transferred from the grippers to the holding devices and after the holding devices have been energized to clamp the transverse filaments to the carrier.

Referring more particularly to Figs. 1, 2, 9 and 10: the form of cutting mechanism 55 employed herein to illustrate the invention, comprises the cutter 115 which may have a rounded or blunt cutting edge 117 adapted to coöperate with a ledge or anvil 119, Fig. 5, on the top of the block 61, referred-to, 60 adjacent the filament-holding teeth 55. A cutter 115 is provided for each of the holding devices, and is secured to a horizontal bar 121 by screws 123 entering through verti-

cal elongated slots 125 on said cutter. This will permit the cutter to automatically adjust and seat itself throughout the entire length of the anvil, and insure its engagement with all of the filaments on said anvil. 65

The cutter-supporting bar 121 may be carried by the arms 127 fast on the shaft 129 70 adapted to rock in bearings 131 depending from a bracket 132 and secured to the truck 19 at the filament supply side of the machine.

When the supply and taking grippers 75 have approached transversely of the machine, the cutter should be elevated so as to be out of the way of said grippers, as will be seen from Fig. 2. To elevate the cutter, the truck carrying the taking grippers may be provided with an arm 133 having an upturned end with a screw 135 tapped therein, and adapted to be held by a lock nut in different positions of adjustment. This screw is adapted to engage an arm 137 projecting upward from and fast on the cutter-carrying rock shaft 129. By this mechanism, it will be apparent that as the grippers approach one another, the screw on the arm 133 will engage the arm 137 and rock 80 the cutters upward shortly prior to the meeting of said grippers.

The cutters should be lowered to sever the filaments after the grippers have moved away from one another transversely of the 95 machine, and to accomplish this, each cutter may be provided with a hammer 139 having a stem 141 adapted to reciprocate vertically in a boss 143 projecting laterally from the bracket 132. The hammer is urged downward by a helical spring 145 confined between the head of the hammer and the lower edge of said bracket.

These hammers are so disposed with respect to the cutters that on the elevation of 105 the latter as described, they will engage the heads of the hammers and thrust their stems upward in said bosses. To hold the hammers cocked in their upward positions, a horizontal lock bar 147 may be provided, Figs. 110 9 and 10, resting upon and adapted to slide along the tops of said bosses. This bar has a series of key-hole slots 149 therein through which the stems of the hammers project. In order to lock the stems in their upward positions, the small ends 151 of the slots are 115 adapted to slide into the circumferential grooves 153 in the hammer stems.

The lock bar should be shifted to the left of Figs. 9 and 10, to lock the hammers in 120 their elevated positions, and should be shifted to the right of said figure to release said hammers. As stated, the bracket 132 supporting the lock bar, is carried by the gripper supporting truck at the supply side of 125 the machine. The movement of the truck

forward and back longitudinally of the machine may be utilized to automatically move said bar to its hammer-locking and releasing positions. To accomplish this, there may be provided a stop arm 155 fast on the machine at a point adjacent the rearward limit of travel of the truck. An adjusting screw 157 in the free end of this arm is adapted to engage an upstanding end 159 of said lock bar when the latter is carried by the truck to a point somewhat short of the rearward limit of travel of the truck. As the truck completes its rearward limit of travel, the hammer stems are moved rearward into the small ends 151 of the key-hole slots and thus are locked in their elevated position. To release the hammers, an arm 161 is provided fast on the machine at a point adjacent the forward limit of travel of the truck, and has an adjustable screw 163 adapted to engage an upstanding end 165 on said lock bar. As a result, as the truck approaches the forward limit of its travel, the upstanding end 165 engages the pin 163, thereby arresting the bar. As the truck continues to complete its forward travel, the hammer stems are moved out of the small ends into the larger ends of the key-hole slots. On the occurrence of this event, they are impelled sharply downward by their actuating springs and strike the cutters with a sharp blow and sever the filaments which extend between said cutters and the anvils coöperating therewith.

The operation of the machine will be readily understood from the foregoing description.

By this invention, simple and effective means is provided for positively transferring the filaments from the grippers to the material to be reinforced; and means for severing the transversely conducted filaments from their source of supply with certainty and precision.

In my copending application, Serial No. 246,644, filed July 25, 1918, is shown and described a mechanism for severing the filaments similar in its broad aspect to the one disclosed herein, but embodying certain details not shown in the present application, such as stop means for limiting downward rocking of the cutter supporting bar after the hammers are energized, and light coil springs normally to hold the cutters up from the distended filaments when the supporting bar is rocked down to its position determined by the stop means.

It will be understood that the invention is not limited to the specific embodiment shown herein for purposes of exemplification, but that extensive deviations may be made therefrom without departing from the spirit and scope of the appended claims.

What is claimed is:—

1. The combination with means for applying filaments transversely of material to be reinforced, of a carrier for receiving the filaments from said means, holding means for the filaments on said carrier, and electrical means for operating said holding means.

2. The combination with means for applying filaments transversely of material to be reinforced, of a carrier for receiving the filaments from said means, and holding means for the filaments on said carrier comprising a series of relatively movable elements for receiving the filaments between them, and electrical means for relatively moving said elements.

3. The combination with means for applying filaments transversely of material to be reinforced, of a carrier for receiving the filaments from said means, and holding means for the filaments on said carrier comprising a comb, fingers between and coöperating with the teeth of the comb for holding said filaments, and electrical means for relatively shifting said fingers and teeth.

4. The combination with means for applying filaments transversely of material to be reinforced, of a carrier for receiving the filaments from said means, holding means for the filaments on said carrier, comprising relatively movable elements, electrical means for shifting certain of said elements in one direction and spring means for shifting the same in the opposite direction.

5. The combination with means for applying filaments transversely of material to be reinforced, of a carrier for receiving the filaments from said means, holding means for the filaments on said carrier comprising fixed teeth, fingers movable relatively to said teeth to clamp the filaments therebetween, and electrical means for operating said fingers.

6. The combination with means for applying filaments transversely of material to be reinforced, of a carrier for receiving the filaments from said means, holding means for the filaments on said carrier, and electrical means for automatically intermittently opening and closing said holding means.

7. In a machine for reinforcing material by transverse reinforcing filaments, the combination with means for simultaneously drawing or distending a plurality of reinforcing filaments transversely of the material to be reinforced, of a carrier movable longitudinally of the machine for receiving the filaments from said drawing or distending means, and holding means for the filaments on said carrier including resilient elements for clamping said filaments.

8. The combination with means for ap-

- plying filaments transversely of material to be reinforced, of a carrier for receiving the filaments from said means, and electro-magnetic means for securing the filaments to said carrier.
9. The combination with means for applying filaments transversely of material to be reinforced, of a carrier for receiving the filaments from said means, a series of electrical devices mounted on said carrier, and controlling means for progressively rendering groups of said devices effective to secure the filaments to said carrier.
10. The combination with means for applying filaments transversely of material to be reinforced, of a carrier for receiving the filaments from said means, electrical devices mounted on said carrier, and means including a commutator for intermittently rendering groups of said devices effective to secure groups of the filaments to said carrier.
11. The combination with means for applying filaments transversely of material to be reinforced, of a carrier for receiving the filaments from said means, electrical holding devices for the filaments mounted on said carrier, and means including a contact rail in the path of said devices for automatically engaging said devices in their transit past said rail.
12. The combination with means for applying filaments transversely of material to be reinforced, of a carrier for receiving the filaments from said means, electrical holding devices for the filaments mounted on said carrier, and means including independent contact rails in the path of said devices for automatically energizing said devices in their transit past said rail.
13. The combination with a carrier, of grippers for applying filaments transversely thereof, electrical holding devices on said carrier for receiving the filaments from said grippers, and means for progressively rendering said devices effective to grip the filaments delivered to said devices from said grippers.
14. The combination with a carrier, of grippers for applying filaments transversely thereof, said grippers being reciprocable forward and backward longitudinally of said carrier, electrical holding devices for the filaments on automatically progressively energizing groups of said devices on forward movements of said grippers.
15. The combination with a carrier, of means for applying filaments transversely thereof, electrical holding devices for the filaments on said carrier, controlling means for progressively intermittently energizing said devices, and controlling means for holding said devices energized for a period on passing the influence of said first-named controlling means.
16. The combination with means for applying filaments transversely of material to be reinforced, of a carrier for receiving the filaments from said means, holding devices for the filaments on said carrier including teeth provided with heads having shoulders and spring fingers movable to and from positions beneath said shoulders.
17. The combination with means for applying filaments transversely of material to be reinforced, of a carrier having holding devices for receiving the filaments from said means, said devices including teeth having tapered heads with offset shoulders and filament clamping fingers reciprocable between said teeth and movable to positions beneath said shoulders.
18. The combination with means for simultaneously applying a plurality of filaments transversely of the material to be reinforced, of a carrier having holding means for simultaneously taking said plurality of filaments from said means, said holding means including relatively movable elements having guiding means for insuring entrance of the filaments properly between said elements.
19. The combination with means for conducting filaments from a source of supply transversely of material to be reinforced, of a carrier for receiving the filaments from said means, holding devices for the filaments on said carrier, electrical means for operating said holding devices, and means for severing said filaments from their source of supply.
20. The combination with a carrier having filament holding devices thereon, of means for conducting filaments from a source of supply to said devices, a cutter means for severing the filaments from their source of supply, and hammer means for operating said cutter means.
21. The combination with a receiver, of means for conducting filaments transversely of said receiver from a source of supply, cutter means for severing the filaments from their source of supply, and hammer means for operating said cutter means.
22. The combination with a receiver, of means for conducting filaments transversely of said receiver from a source of supply, an anvil, a cutter, and hammer means for impelling said cutter toward said anvil to sever the filaments from their source of supply.
23. The combination with a receiver, of means for conducting filaments transversely of said receiver from a source of supply, an anvil, a blunt cutter, and hammer means for impelling said cutter toward said anvil to sever the filaments from their source of supply.
24. The combination with a receiver, of

- means for conducting filaments transversely of said receiver from a source of supply, and means for severing the filaments from said source of supply including separable members for receiving the filaments between them and means for impelling one of said members toward the other. 50
25. The combination with a carrier, of means for conducting filaments transversely of said carrier from a source of supply, a series of holding devices for said carrier for receiving the filaments from said means, and a cutter for each of said devices for severing the filaments from their source of supply. 55
- 10 26. The combination with a link carrier, of means for conducting filaments transversely of said carrier from a source of supply, and means for severing the filaments from said source of supply including a cutting member on each link of said carrier. 60
- 15 27. The combination with a carrier, of means for conducting filaments transversely of said carrier from a source of supply, holding devices on said carrier for receiving 65 the filaments from said means, a cutter member for each of said devices, and cutter members coöperating with said first-named cutter members and mounted independently of said holding devices. 70
- 20 28. The combination with means for conducting filaments transversely of material to be reinforced from a source of supply, of means for reciprocating said conducting means longitudinally of said material, and 75 means for severing said filaments from said source of supply including cutter means, hammer means for operating said cutter means, means to cock said hammer means on movement of said conducting means in one 80 direction, and means to release said hammers on movement of said conducting means in the opposite direction. 85
29. The combination with means for conducting filaments transversely of material to be reinforced from a source of supply, means for reciprocating said conducting 90
- 40 45

means longitudinally of said material, and means for severing said filaments from said source of supply including cutter means, hammer means for operating said cutter means, and means for automatically cocking and releasing said hammer means. 50

30. The combination with a carrier, of means for conducting filaments transversely thereof from a source of supply, and means 55 for severing said filaments from said source of supply including cutter members, a bar carrying the same, and hammers for impelling said cutter members toward said carrier. 60

31. The combination with a carrier, of means for conducting filaments transversely thereof from a source of supply, and means for severing said filaments from said source of supply including cutter members, a bar carrying the same, and spring pressed hammers for impelling said cutter members toward said carrier. 65

32. The combination with a carrier, of means for conducting filaments transversely thereof from a source of supply, means for 70 severing said filaments from said source of supply including cutter members, spring pressed hammers for operating said cutter members, and means for automatically cocking said hammers. 75

33. The combination with means for conducting filaments transversely of material to be reinforced from a source of supply, means for reciprocating said conducting means longitudinally of said material, means 80 for severing said filaments from said source of supply including cutter means, hammer means for operating said cutter means, means for automatically cocking said hammer means on movement of said conducting 85 means in one direction, and means for automatically releasing said hammer means on movement of said conducting means in the opposite direction. 90

In testimony whereof, I have signed my name.

CHARLES H. HOWARD.
